(57) **CLAIM**

The ornamental design for a sexual stimulator, as shown and described.

DESCRIPTION

FIG. 1 is a front view of a sexual stimulator in accordance with the new design;

FIG. 2 is a right side view thereof;

FIG. 3 is a rear view thereof;

FIG. 4 is a left side view thereof;

FIG. 5 is a top view thereof;

FIG. 6 is a bottom view thereof; and,

FIG. 7 is a front perspective view thereof.

The broken lines in the drawings depict portions of the sexual stimulator that form no part of the claimed design. The sexual stimulator can include a vibrator for stimulating various body parts. In particular, the sexual stimulator is intended to be used for health and sexual pleasure.
